UNITED STATES PATENT OFFICE.

HENRY L. FERRIS, OF HARVARD, ILLINOIS, ASSIGNOR TO HUNT-HELM-FERRIS & COMPANY, OF HARVARD, ILLINOIS, A CORPORATION OF ILLINOIS.

OVERHEAD TRACK.

1,282,403.

Specification of Letters Patent. Patented Oct. 22, 1918.

Application filed March 23, 1918. Serial No. 224,153.

To all whom it may concern:

Be it known that I, HENRY L. FERRIS, a citizen of the United States, residing at Harvard, in the county of McHenry and State of Illinois, have invented a new and useful Improvement in Overhead Tracks, of which the following is a specification.

My invention relates to certain new and useful improvements in overhead tracks and is fully described and explained in the specification and shown in the accompanying drawings, in which:

Figure 1 is a side elevation of my improved device; Fig. 2 is a longitudinal section; Fig. 3 is a section on the line 3 of Fig. 2; and Fig. 4 is a section on the line 4 of Fig. 2.

Referring to the drawings:

5 is a rigid track carried by bracket 6 from the frame-work of a building. 7 is a coupling member carried by a heavy bracket 8. This coupling member is engaged at one end by the rigid track and from it extends at the opposite end, the flexible track 9 of round rod. For the purposes of the present invention, the flexible member may be either fastened in or passed through the coupling member 7 in any desired manner, the support here shown being the offset lateral support of my patent on overhead track No. 1,003,097 dated September 12, 1911.

In the use of combined flexible and rigid tracks of the form shown in said patent, or of other analogous forms, it has been found in practice that the sudden drop of a heavily loaded litter-carrier to the yielding flexible track has a tendency to bend the flexible track quite sharply at, or adjacent to, the point where it enters the coupling member.

40 This sudden repeated and powerful bending action in some cases crystallizes the flexible track, the speed of crystallization depending upon the quality of steel employed in the flexible track. The tendency to crystallize has always been present to such an extent that by far the greater number of breaks in the track occur approximately at the point described, and recently the condition of the steel industry has produced such changes in

the steel commonly employed in the manufacture of round rods, as to make breakages much more frequent. The structure herein shown, however, greatly reduces the difficulty and makes the track much more durable.

55 In my improvement, the outer end of the coupling member has downwardly-turned ears 10 and immediately in front of it is a hinged member 11 provided with similar ears 12, both sets of ears being pivoted to a supporting bar 13. The hinged member 11 is of channel form, the flexible track running through it, and at its outer or forward end are ears 14, between which is carried a filler-block 15 by which the flexible track is held in place.

60 By this arrangement, the flexible track is given two separate points at which it may bend, and the amount of bend in each place is thus distinctly decreased. When the wheel 70 of a carrier runs over the coupling member on to the hinged member, there is a relatively small bend, and this of a controlled character over the supporting bar 13; and when the wheel runs off the hinged member on to the 75 flexible track proper, there is no such tendency as before existed, sharply to bend the track and crystallize it.

75 I realize that considerable variation is possible in the details of this construction without departing from the spirit of my invention; therefore I do not intend to limit myself to the specific form herein shown and described except as pointed out in the following claims, in which it is my intention to 80 claim all the novelty inherent in the construction as broadly as is permitted by the state of the art.

85 What I claim as new and desire to secure by Letters Patent is—

90 1. In combination, a rigid track, a flexible track, a coupling member interposed between the rigid track and flexible track and into which the flexible track enters, and an intermediate hinged member pivotally secured to 95 the coupling member and overlying the adjacent portion of the flexible track whereby to distribute the bend of the flexible track to

the two sides of the intermediate hinged member.

2. In combination, a rigid track and coupling member secured thereto and a flexible track entering into the coupling member, an intermediate hinged member overlying the adjacent part of the flexible track, and a supporting member underlying the junction

point of the coupling member and intermediate hinged member and pivoted to both said members and underlying the flexible track whereby upon the application of loads to the flexible track, to distribute the bend thereof.

HENRY L. FERRIS.
